Attorney

UNITED STATES PATENT OFFICE.

JOSEPH I. SCHWARTZ, OF DENVER, COLORADO.

DEMOUNTABLE JEWEL.

Application filed May 1, 1928. Serial No. 274,175.

This invention relates to a mounting for the jewels and ornaments on rings, pins, brooches, clasps, and other articles of jewelry.

It is the present fashion to have the stones in the jewels of the wearer match in color the dresses and gowns. This necessitates a large number of similar pieces of jewelry, each having stones of different color. The principal object of this invention is to construct a jewel mounting which will allow the stone to be quickly and easily changed so that the piece of jewelry can be repeatedly used with differing stones. Thus, the wearer can quickly change the color of her jewels to match 10 the particular dress or gown she intends to wear with them.

Another object of the invention is to construct a demountable mounting which will absolutely lock the stone in place so as to eliminate any possibility of loss thereof.

A still further object is to construct a demountable mounting so that it will not detract or mar the design of the piece of jewelry.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

35 In the drawing:

Fig. 1 is a side elevation of a finger ring in which the invention is embodied.

Fig. 2 is a top view of the ring of Fig. 1 with the jewel and bezel removed.

40 Fig. 3 is a side elevation of the ring with the stone and bezel removed.

Fig. 4 illustrates two detail side elevations of the bezel which is employed for holding the stone in place.

45 Fig. 5 is an enlarged cross section taken on the line 5—5, Fig. 1.

Fig. 6 is a detailed cross section taken on the line 6—6, of Fig. 3, illustrating two methods for holding the bezel in place.

50 Fig. 7 is a side elevation of an alternate form of bezel.

The invention will be described as pertaining to a ring but it is to be understood that this is simply for illustrative purposes, as the 55 invention will be equally useful for maintain-

ing a stone in any article of jewelry or the like.

In the drawing the ring proper is illustrated at 10, and is formed with a hollow stone supporting sleeve 11, around which is an annular depression 12. The stone, illustrated 60 at 13, is set upon the sleeve 11, and a bezel 14 is fitted over both the stone and the sleeve 11.

The bezel is illustrated in detail in Fig. 4 and comprises a band portion 15 which surrounds the sleeve 11 having an inwardly turned flange 32 for holding the stone in place. The band portion 15 may be engraved with any suitable design in harmony 65 with the design of the ring 10.

Depending from the portion 15 are two legs 16 and 17 which are received in openings 18 and 19, respectively, formed through the ring 10 at the sides of the sleeve 11.

The leg 17 is provided with a dove-tailed 75 catch 20 hinged thereto as shown at 21. On the inner face of the ring 10 a dove-tailed notch 22, see Fig. 6, is formed which receives the catch 20 when the bezel is in place. The catch 20 may be raised from its notch by 80 inserting a pointed instrument, such as a pin, into a groove 23 formed alongside of the notch 22. When the catch 20 is in alignment with the leg 17 the bezel 15 can be easily lifted 85 from the sleeve 11 so as to allow the stone 13 to be removed. It will be noted that there are no metal parts permanently attached to the stone so that any desired stone can be quickly put in place without requiring a mechanic.

When the catch 20 is in place in its notch 22, 90 the finger of the wearer prevents it from leaving its notch and turning upon its hinge 21, so that, while the ring is being worn the stone is positively locked in place.

The design of the ring can be brought up- 95 wardly around the annular groove 12 as shown at 24 so as to entirely conceal the base of the bezel 15 and give the ring the appearance of having a solid permanent mounting.

In Figs. 6 and 7, I have illustrated an alternate method of locking the bezel in place. In this form, a sliding latch member 25 is secured in a groove 26 on the inner face of the ring, by means of a riveted head 27. The head 27 can be formed by raising a projection on 105 the metal of the ring and upsetting this projection after the member 25 is in place. The member 25 is provided with an elongated opening 28, which allows it to slide under the head 27. It also carries a tongue 29 which 110

slides into an opening 30, see Fig. 7, in a leg of the bezel and firmly locks the bezel in place.

In Fig. 6 I have illustrated a ring constructed for both methods of attachment. If desired, they both can be used by providing the bezel leg 17 with the catch 20 and the leg 16 with the opening 30. It is not always necessary, however, to use both forms of the catch on a single mounting, either can be used independently if desired.

The sleeve and bezel, as illustrated, are cylindrical for receiving a round stone. They are not, however, limited to this shape but may be made to conform to any desired shape of stone. For the larger stones more of the legs 15 could be used to secure the bezel in place.

The invention has been described as employing a bezel or flange surrounding the edge of the stone. It will operate equally well, however, if the band 15 is filigreed or scalloped at its upper edge or with prongs formed on the band to secure the stone in place of the flange 32. It is to be understood that the term bezel in the description and claims includes any similar member adapted to extend over and hold the stone in place.

While a specific form of the improvement has been described and illustrated herein, it is desired to be understood that the same may be varied, within the scope of the appended claims, without departing from the spirit of the invention.

Having thus described the invention, what I claim and desire secured by Letters Patent is:—

1. A mounting for jewels and the like comprising a base member; a sleeve formed on and projecting from said base member and adapted to support said jewel; a bezel member 40 adapted to surround said sleeve and extend partially over said jewel so as to hold said jewel against said sleeve; and means for holding said bezel in place, said means comprising a projecting member carried by one of said

members and adapted to engage an opening in the other of said members.

2. Means for maintaining a stone on an article of jewelry comprising a sleeve projecting from said article; a depression in said article surrounding said sleeve; a bezel adapted to fit over said sleeve and enter said depression so as to maintain said stone between said bezel and said sleeve; and means for locking said bezel in place.

3. Means for maintaining a stone on an article of jewelry comprising a sleeve projecting from said article; a depression in said article surrounding said sleeve; a bezel adapted to fit over said sleeve and enter said depression so as to maintain said stone between said bezel and said sleeve; and means for locking said bezel in place, said means comprising a leg on said bezel adapted to pass into said article and a hinged extremity on said leg acting to prevent its withdrawal from said article, said extremity having a dovetail-like contour and a dovetail-like depression in said article to receive said extremity.

4. A mounting for jewels and the like comprising a base member; a sleeve formed on and projecting from said base member and adapted to support said jewel; a bezel member adapted to surround said sleeve and extend partially over said jewel so as to hold said jewel against said sleeve; and means for holding said bezel in place.

5. Means for detachably mounting a loose jewel on an article of jewelry comprising: a hollow sleeve permanently attached to and projecting from said article; a bezel arranged to slide over the projecting extremity of said sleeve and maintain said jewel thereagainst; and means for locking said bezel in place, said locking means being arranged so as to allow withdrawal of said bezel from said sleeve when desired.

In testimony whereof, I affix my signature.
JOSEPH I. SCHWARTZ.
